BEACHING GEAR

Owen E. Tormellan, Jr., Raspeburg, Md., assignor
to The Glenn L. Martin Company, Middle
River, Md., a corporation of Maryland

Application October 28, 1943, Serial No. 507,954

6 Claims. (Cl. 280—61)

This invention relates to a beaching gear for boat hulls and is particularly adapted for beaching large flying boats.

The difficulty of handling a large flying boat to get it into the water and out of the water is well known. Many expedients, such as a cradle which is slipped under the hull, have been tried, but the difficulty in getting such a cradle under a hull in the water and properly aligned with certain structures in the hull designed to bear the load when the cradle removes the hull from the water, should be obvious, and accounts for this method of handling such flying boat hulls to be abandoned for a large craft.

By this invention, the beaching gear for flying boat hulls is provided which is simple and compact in construction.

Another object of the invention is to provide a beaching gear which may, if necessary, be carried in the bomb bays of the craft.

Another object of the invention is the provision of a beaching gear which may be floated into place and quickly and easily secured to the craft.

Another object of the invention is the provision of the braking mechanism on the beaching gear for the control of the craft when on shore.

A further object of the invention is the provision of a swiveling device on the beaching gear to enable the beaching gear to be turned with respect to the craft for lateral motion of the craft.

A further object of the invention is the provision of a beaching gear secured to the hull at two points and means to align the beaching gear after the first point of support has been secured with a second point of support.

Further and other objects will become apparent from the description of the accompanying drawings which form a part of this disclosure and in which like numerals refer to like parts.

In the drawings:

Figure 1 is a side elevational view, partly in section, showing the beaching gear attached to the hull of the craft.

Figure 2 is a front view of the beaching gear attached to the hull of the craft.

Figure 3 is a fragmentary perspective view of a portion of the beaching gear showing the hydraulic brake and jack arrangement.

Figure 4 is a fragmentary perspective view showing one attachment to the craft.

Figure 5 is a fragmentary section showing the other attachment to the craft.

The beaching gear of this invention is generally illustrated in Figures 1 and 2. The beach-

ing gear consists of an upper bracket generally indicated as 1 which is adapted to be attached to the hull 2 at two points. The second portion of the beaching gear is generally indicated as 3.

5 This portion affords a mount for the pneumatic-tired wheels 4. Portions 1 and 3 are pivoted as shown in Figure 5 so that bracket 1 may be securely fixed to the hull at two points and portion 3 carrying the wheels, may be turned relative thereto.

It will be noted in Figure 1 that portion 1 of the beaching gear is generally normal to the chine line 5 of the hull 2 because the chine line at this point is generally parallel to the normal water line of the craft afloat. The plate portion 6 of member 3 is generally parallel to the ground line because when the craft is out of the water, the tail beaching gear causes the hull to assume the attitude with respect to the ground line, generally illustrated in Figure 1. This description of the beaching gear attached to the hull afloat for supporting it ashore, is intended to explain the out-of-line construction of the beaching gear illustrated in Figure 1.

25 Portion 1 is adapted to be attached to the hull at two points. This portion or bracket consists of member 7 which telescopes with member 8. Member 8 is secured to a casting 9 which has an in-turned portion or seat 10 having pad 11 thereon to protect the finish on the hull. Pins 12, shown in Figure 5, register with two holes in the chine of the hull to secure seat 10 when in place, from inadvertently being displaced laterally of the chine. The lower portion of casting 9 is formed

30 to pivot on, and with respect to, portion 6 of member 3. This lower portion will subsequently be described in more detail. On telescoping member 7, a fitting 13 is secured which supports the pivoting head and attaching bracket, consisting of a support 14 rigidly secured to fitting 13. Attaching bracket 15 is pivoted on support 14 at pivot 16. Bracket 15 is formed with slots 17 which are adapted to engage levers 18 extending from a support in member 19 in the side of the hull 2. Knobs 20 operate pins 21 which pass through holes 22 when levers 18 are placed in slots 17 in bracket 15. Handle 23 is provided on bracket 15 to facilitate pulling this end of the beaching gear from its floating position in the water to

35 engagement with levers 18. From a consideration of Figures 1 and 4, it will be noted that bracket 15 pivots about an axis generally parallel to the waterline through pins 21 by hinge 24. This permits bracket 15 to be pulled up out of the water 40 while the beaching gear is afloat and attach it to

45

50

55

levers 18. One end of the beaching gear will then be attached to the hull by bracket 15, while the other end is floating substantially normal to the side of the hull. It is then necessary to pivot the beaching gear attaching bracket downwardly through the water, under the hull of the ship and align pins 12 with the holes in the chine. Due to the fact that bracket 15 is pivoted at 16 on support 14, it is necessary to lock bracket 15 with respect to 14 so that when the beaching gear is pushed under water, the arc of travel will be fixed due to the fixed relationship between portion 1 and bracket 15. This is accomplished by tapered pin 25 which aligns and holds portion 26 on which bracket 15 pivots, with respect to support 14. When pins 12 are aligned with the holes in the chine, lever 27 operates linkage 28 so that the telescopic motion of members 7 and 8 will pull pins 12 upwardly into engagement with the holes in the chine which will then be seated on pad 11. Latch 29 holds lever 27 in the upward position to maintain pins 12 in the holes in the chine.

From the above description, it will be seen that the beaching gear may be floated into position along side the hull and by means of handle 23, bracket 15 will be attached to levers 18. Pin 25 is inserted in the aligned holes in members 26 and 14 so that the only relative motion of the beaching gear with respect to the hull of the ship will be about a fixed axis so that the weight of one or two men standing on the float will cause the beaching gear to sink under the ship and align pins 12 with holes in the chine. Lever 27 is then operated to draw portion 8 and seat 10 upwardly to engage the bottom of the hull.

The pivoting of bracket 15 with respect to the top of the beaching gear in two directions is necessary because it is more than likely that the beaching gear will rock either gently or violently, depending upon the water and without this pivoting in two directions, it would be practically impossible to align levers 18 in slots 17 in bracket 15. Once they are aligned and pins 21 driven home, the beaching gear can be restrained against further rocking motion by means of pin 25.

Tank 30 is a float attached to casting 9 and portion 8. Handles 31 are mounted on the float to facilitate handling the float separate or when attached to the beaching gear when in the water. It should be understood that the beaching gear can be used with or without float tanks 30. Casters 32 form a third point of support so that the beaching gear may be moved about when on the ground separate from the ship.

Hydraulic cylinder 33 is mounted on the pedestal 3 to transmit fluid pressure to brakes 34 on the pneumatic-tired wheels of the beaching gear. This hydraulic cylinder is operated by lever members 35, the outer section of which 36 extends beyond the wheel and is pivoted at 39 for stowing. The brake cylinder may be actuated by a man standing off the side of the beaching gear. Rack 37 and pawl 38 act as a locking means for the handling of the hydraulic cylinder.

At the lower portion of pedestal 3 there is incorporated an inverted hydraulic jack 40 having foot 41 adapted to be extended and retracted by means of hydraulic pressure from cylinder 42 operated by handle 43. This hydraulic jack serves two purposes. If it is necessary to change a tire on the beaching gear when in position on a boat hull, the built-in jack facilitates the changing of the tire in the conventional manner, but a more important purpose is served by this built-in jack as a swiveling device in handling

the flying boat. When it is necessary to maneuver the ship on the ground or in and out of a hanger, it is often desirable or necessary due to lack of space, to move the ship side ways. When beaching gear of the type herein described is employed to support a ship of 170,000 pounds, the load on the tires is such that even with the pivoting of pedestal 3, the drag on the tires around the pivot point is considerable and damage to the tire will result if an attempt is made to swivel the gear on the two tires. For this reason the jack 41 plays an important part. It can be lowered into contact with the ground and the wheels raised sufficiently, so that the tires will be clear of the ground, or in other words, the weight of the ship can be shifted from the tires to the hydraulic jack and the jack swiveled to any angular position. By turning valve 44, the pressure is released and the wheels are again let down in contact with the ground for maneuvering the ship.

Bolt 45 serves to lock the pedestal 3 with respect to the supporting bracket in any position.

A section through the portion of the beaching gear pivot is illustrated in Figure 5. Roller bearings 46 and central pivot 47 afford the swiveling connection between portions 10 and 6. Grease is supplied through fitting 48 to passages 49, 50 and 51 to lubricate the sleeve bearings 52 and 53 and also fill the space 54 between members 6 and 10 out to the labyrinth seal 55. This grease packing protects bearings 46, 52 and 53 when the beaching gear is submerged.

Ring 56 affords a connection for a tow line. Hole 57 extends into the pedestal 3 so that a bar or lever may be inserted to aid in swiveling the beaching gear pedestal 3 when supported on the hydraulic jack.

While any number of beaching gear units herein described, may be employed in beaching a craft, it is usual in handling a flying boat to secure one on each side of the hull slightly forward of the center of gravity and one at the tail. With this arrangement, it can be seen that the beaching gear near the center of gravity takes substantially the whole weight of the ship.

It is to be understood that certain changes, alterations, modifications and substitutions can be made without departing from the spirit and scope of the appended claims.

I claim as my invention:

1. A beaching gear for flying boat hulls for maneuvering said flying boat ashore, comprising a frame, a portion of said frame being removably secured to said hull, a pair of wheels secured to another portion of said frame, said wheel mounting portion being pivoted to said portion secured to the hull about a substantially vertical axis, a jack member mounted on said frame intermediate said wheels substantially coaxial with said pivot point, power means to extend said jack member from said frame into contact with the ground whereby the load may be transferred from said wheels to said jack member for swiveling said beaching gear to permit sidewise motion of said flying boat.

2. A beaching gear for flying boat hulls for maneuvering said flying boat ashore comprising a supporting frame, a portion of which is removably secured to said hull, a pair of pneumatic-tired wheels secured to a portion of said frame which is pivoted to said portion being secured to said hull, for turning about a substantially vertical axis, a jack member mounted on said frame between said wheels substantially coaxial with

said pivot point, hydraulic power means for extending said jack member into contact with the ground to transfer the load of the flying boat from said wheels to said jack for swiveling said beaching gear to permit sidewise movement of said flying boat.

3. A beaching gear for flying boat hulls comprising a supporting frame, hinged locking means thereon to secure one end of a portion of said frame to the hull, said supporting frame having a portion formed to extend under and support the hull, a pair of pneumatic-tired wheels secured to a portion of said frame which is pivoted to said first portion for turning about a substantially vertical axis, an inverted hydraulic jack member mounted on said frame between said wheels substantially coaxial with said pivot point, hydraulic power means to extend said jack member into contact with the ground to raise said frame whereby the load may be transferred from said wheels to said jack for swiveling said beaching gear.

4. In a beaching gear for flying boat hulls having a supporting frame, comprising an attaching bracket, one end of which having hinged locking means thereon to secure said end to the side of the hull, said bracket having a portion formed to extend under and support the hull, pin means on said formed portion adapted to cooperate with holes in the hull, a telescopic section in said bracket whereby said formed portion may be moved relative to said hull bottom and said

means to align said pins with the holes in the hull bottom.

5. A beaching gear for flying boats of the type adapted to be floated along side the hull for attachment thereto, comprising a supporting bracket adapted to be secured to the hull at two points, one end formed to support the chine of the hull, having pins thereon to engage holes in the chine, an attaching member on the other end of said bracket pivoted thereto about an axis substantially parallel to the hull of the craft, and about another axis normal to the hull, to facilitate securing said attaching member to the hull in rough water, means to lock said bracket against motion relative to said attaching member when the latter is in place, so that when said bracket is pivoted about the axis substantially parallel with the hull, said pins will be aligned with the holes in the chine.

20 6. A beaching gear for flying boats of the type adapted to be floated along side the hull for attachment thereto, having an attaching bracket portion adapted to be secured to the hull, means to secure said bracket portion to the boat hull comprising an attaching member pivoted for motion about an axis substantially parallel to the hull and about another axis substantially normal to the hull to facilitate attaching said bracket in rough water, and means to restrain the motion about the axis normal to the hull after the bracket has been attached.

OWEN E. TORMOLLAN, JR.
